UNITED STATES PATENT OFFICE.

ADOLF MESSER, OF FRANKFORT-ON-THE-MAIN, GERMANY.

APPARATUS FOR CUTTING METAL.

1,139,048.

Specification of Letters Patent.

Patented May 11, 1915.

Original application filed June 29, 1911, Serial No. 636,112. Divided and this application filed October 31, 1912. Serial No. 728,819.

To all whom it may concern:

Be it known that I, ADOLF MESSER, a subject of the Emperor of Germany, residing in the city of Frankfort-on-the-Main, Germany, have invented certain new and useful Improvements in Apparatus for Cutting Metal, of which the following, taken in connection with the accompanying sheet of drawing, is a full, clear, and concise description.

This application is a division of application filed by me on June 29, 1911, Serial Number 636,112.

The present invention relates to the construction of a tool used for the above-stated purpose and comprehends certain details of construction which, in their combination, constitute a simplified and easily-operated tool.

20 A further object of my invention is to provide means whereby nozzles of different forms may be used and are, therefore, interchangeable with respect to the handle portion of the tool.

25 Further objects of my invention are to provide means whereby the nozzles may be angularly disposed or positioned with relation to the surface being worked upon, and also the provision of means for securing a circular cut.

30 A further object of the invention is to provide a simple, effective, and convenient means for controlling the gas supply for the cutting flame.

35 These and other objects will be more clearly understood from a reading of the following specification.

In the drawing forming a part of this specification, Figure 1 is a central, longitudinal, sectional view of a preferable form 40 of my improved cutter, the hand-lever being shown in full. Fig. 1^a is a cross-sectional view of the nozzle shown in Fig. 1, taken on line A—A. Fig. 2 is a central sectional view of a different form of nozzle used for supplying two supporting flames. Fig. 2^a is a cross-sectional view taken on line A—A of Fig. 2. Fig. 3 is an end elevation of the device showing the means for 45 controlling the angle of cut relative to the surface worked upon, Fig. 4 is an enlarged view of one of the tractors assembled, and, Fig. 5 is an end elevation of the device equipped with a radius bar and positioned 50 for cutting at an angle to the surface worked upon.

The outer tube 7 constitutes the handle for the cutter and is secured to the head 8. The head 8 has in the present showing an integral tube 9, disposed within the tube 7, and of such dimensions relatively thereto that a gas passage or chamber 10 will be provided between the inner wall of one tube and the outer wall of the other. The bore of the tube 9 constitutes a gas chamber or 55 passage 11. Gas will be supplied to these chambers or passages from suitable sources through connections 12 and 13 respectively, and which connections are, in the present illustration, controlled by a single valve 14. 60 Both tubes 7 and 9 are connected to the head portion 15. The nozzle 16 is shown secured to the head by a coupling 17.

For convenience of description it will be assumed that the oxygen is supplied to passage 11 and a coöperative heating gas to passage 10.

The nozzle is shown provided with a mixing chamber 18'. A channel 19 leads from the gas passage 10 to the mixing chamber. 80 Oxygen will pass from the passage 11 into the central passage 20 of the head and when the valve 21 is closed on its seat 22, through channel 23, into the mixing chamber 18'. The mixed gases for the heating flame will 85 pass out of the nozzle orifice 24 and produce a heating and supporting flame. The valve 21 closes the channel 25 and nozzle orifice 26 against the flow of oxygen until such time as the heating flame has done its 90 work and the cutting flame is to be brought into action. Upon raising the valve 21 from its seat, the flow of oxygen will be divided, part going to the mixing chamber for supplying the heating gas, and the 95 larger portion, under less obstruction, passing to supply the cutting flame.

A convenient means for actuating the valve 21 is illustrated. A hand-lever 27 is mounted on a fulcrum-support 28, and engages an eye in the valve-stem 29. The lever is provided with a finger-hook 30, and a thumb-piece 31.

The burner or nozzle portion of the device is made removable as shown, the same 105 being held in position by a screw-coupling 17. This provides a very convenient means for removing the burner and makes accessible the interior valve mechanism for adjustment or cleaning purposes. At the same 110 time, different forms of burners may be conveniently used with one operating tool.

The form of burner shown in Fig. 2 is used where forward and rearward supporting flames are desirable or required.

In blow-pipes used for cutting iron by means of oxygen, in which one heating flame is employed for preceding the oxygen ray in order to produce the temperature required for oxidation, the disadvantage is experienced that by the striking of the cutting flame or oxygen ray on the iron to be cut a pressure is exerted on the flame which is deflected and diffused. Hence the cuts necessitate a powerful oxygen ray and therefore a large expenditure of oxygen. Notwithstanding this, the cuts in most cases become rough. The ring-shaped heating flames support the oxygen in some measure during the cutting, but the lateral parts of the iron or the cutting edges of the same are melted down and fail to remain sharp-edged.

In the form of burner illustrated in Fig. 2, two heating gas orifices are provided, 24, 24'', for furnishing the cutting flame with two heating flames; namely, one which precedes the oxygen ray for producing the temperature required for oxidation, and another which follows it in the cutting crevice by means of its high emission speed. The last-mentioned heating flame following the heating ray performs this important work without the noxious consequences of the ring-shaped heating flame consisting in the melting down of the cutting edges, and besides insures a smooth cut and effects great economy in gas.

For the purpose of holding the cutting flame at the desired angle to the surface of the material being worked upon, the head in Fig. 3 is shown provided with a pair of adjustable tracker-wheels 32, 32. Each wheel has its axle carried by a slide 33. The slides are provided with longitudinal slots 34, adjustably held to a yoke 35, by set-screws 36 and nuts 37. The set-screws also serve to clamp the yoke in position on the head. By the adjustment of the slides the angle of the flame can be determined. This assures the precise and even cutting of bevels.

One of the screws 36 is shown provided with a socket 38 and an external screw-thread 39 for the attachment of a radius-bar 40. The radius-bar has a ball 41 for the socket, which ball will be held in place by a coupling 42. The radius-bar carries a center-pin 43 which by means of a set-screw 44 is adjustable longitudinally of the bar for determining the radius of cut, and by means of a set-screw 45 is adjustable transversely for effecting the angularity of the flame to the axis of the cutting movement.

I do not limit myself to the precise details,

since changes may be made within the scope of the claims.

Having thus described my invention, what I claim as new herein and desire to secure by Letters Patent is:

1. In a cutter, the combination with a burner nozzle, a yoke mounted thereon, a pair of wheels carried by said yoke and independently adjustable one relatively to the other.

2. In a cutter, the combination with a cutter head provided with a flame detachable nozzle and a pair of supports located upon opposite sides of said nozzle and independently adjustable for controlling the angle of the cut.

3. In a flame cutter, the combination of a detachable nozzle and adjustable means carried thereby for engaging the surface acted upon for regulating the angle of the cut relatively to such surface.

4. In a flame cutter, the combination with a nozzle, of means carried thereby for engaging the surface of material acted upon, an adjustable radius-bar secured to said nozzle, and an adjustable axis point for said radius-bar.

5. In a flame cutter, the combination with a nozzle, of means adjustably carrying the nozzle for regulating the angle of the flame to the surface worked upon, an adjustable radius-bar carried by such nozzle, and an adjustable axis carried by said radius-bar.

6. The combination with a cutter adapted for use with interchangeable flame nozzles, of a pair of supports located upon opposite sides of said cutter and independently adjustable for controlling the angle of the cut.

7. The combination with a cutter provided with an interchangeable nozzle connection, of a yoke mounted thereon, a pair of wheels carried by said yoke and independently adjustable one relatively to the other to control the angle of the cut.

8. The combination with a cutter adapted for use with interchangeable flame nozzles, of means for controlling the angle of the cut, said means comprising a yoke adjustably secured to said cutter, a pair of supports mounted on the opposite ends of said yoke, and means for adjusting said supports relatively to said yoke and to each other, each of said supports being provided with a roller adapted to travel upon the work.

In witness whereof I have hereunto set my hand in the presence of two subscribing witnesses.

ADOLF MESSER.
